Primary Examiner — Christy Nemeth(74) *Attorney, Agent, or Firm* — Lando & Anastasi, LLP(57) **CLAIM**

The ornamental design for an uninterruptible power supply, as shown and described.

DESCRIPTION

FIG. 1 is a perspective view of an uninterruptible power supply of our new design;

FIG. 2 is a right side elevational view thereof;

FIG. 3 is a left side elevational view thereof;

FIG. 4 is a front elevational view thereof;

FIG. 5 is a back elevational view thereof;

FIG. 6 is a top plan view thereof; and,

FIG. 7 is a bottom plan view thereof.

The broken lines in the drawings illustrate portions of the article that form no part of the claimed design.
